LUBRICATING DEVICE

Filed Aug. 21, 1933

position above said center; thus the lower weight will be exerting a downward thrust and having greater leverage than the upper weight, will overbalance said upper weight.

5 When the grease stick B is first placed in the box the lever 26 will be swung to its upper position as is shown in dotted lines in Figure 1. The lower weight 28 will swing the lever downward, whereby the link 21 will slide the follower 20 forwardly and force the grease stick B into contact with the rail A and the guides 16. This will require a short travel of the parts and thereafter, as the stick wears it will be advanced by the downward swing of the lever.

15 After the initial movement of the lever 26 the upper weight 28 will be moved from its neutral position and begin to co-act with the lower weight in swinging the lever. It is obvious that these weights will complement each other as the downward swing continues, thereby assuring a substantially uniform pressure throughout the swing. By this arrangement the weights equalize the pressure and produce substantially a uniform feed. If two weights were not provided and only a single weight were used, the force exerted to feed the grease stick would vary in proportion to the leverage. Consequently, when the stick was almost consumed, as is shown in Figure 1, and when it was first fed, it would not be under as great pressure as it would be in intermediate feeding positions. The two weights equalize the pressure and tend to assure a uniform feed.

30 The operation and refilling are very simple. By loosening the thumb bolt 19, swinging the lid 17 upwardly, and then lifting the lever 26, the follower 20 is withdrawn and the parts are ready to receive the grease stick. All of this may be done without the use of tools, easily and quickly. After the grease stick is placed in the box the lever may be released and the lid fastened. No further attention need be given the device until the grease stick is worn out.

35 The description which has been given recites more or less detail of a particular embodiment of the invention which is set forth as new and useful, however, I desire it understood that the invention is not limited to such exact details of construction, because it is manifest that changes and modifications may be made within the scope of the appended claims, without departing from the spirit of the invention.

40 What I claim and desire to secure by Letters Patent, is:

45 1. In a lubricating device, an elongated box having a slot in its forward end for receiving a guide rail and also provided with guides directed toward said slot for crowding grease toward the same, a follower slidably mounted in the box for feeding a stick of grease toward the slot, a sector-shaped lever having divergent legs pivoted on the rear end of the box, weights mounted on the legs of the lever, and a link connecting the lower leg of the lever with the follower.

50 2. In a lubricating device, an elongated box

having a slot in its forward end for receiving a guide rail and also provided with guides directed toward said slot for crowding grease toward the same, a follower slidably mounted in the box for feeding a stick of grease toward the slot, a sector-shaped lever having divergent legs pivoted on the rear end of the box, weights mounted on the legs of the lever, a link connecting the lower leg of the lever with the follower, the box having a slot in its rear end through which the link passes and for receiving the connections between the link and the follower, whereby the follower may stand flush against the rear end of the box, and a lid mounted on the box.

55 3. In a lubricating device, an elongated box having a slot in its forward end for receiving a guide rail and also provided with guides directed toward said slot for crowding grease toward the same, a follower slidably mounted in the box for feeding a stick of grease toward the slot, a lever pivoted on the rear end of the box, a weight mounted on the lever, a link connecting the lever with the follower, and a shoe on the link for limiting the tilting movement of the follower.

60 4. In a lubricating device, an elongated box having a slot in its forward end for receiving a guide rail and also provided with guides directed toward said slot for crowding grease toward the same, a follower slidably mounted in the box for feeding a stick of grease toward the slot, an upright standard on the rear end of the box, a sector-shaped lever having divergent legs pivoted at its apex at the upper end of the standard, weights adjustably mounted on the legs of the lever, and a link pivotally connected with the lower leg of the lever and the follower.

65 5. A lubricator for elevator car guide rails comprising, an elongated box having an upright slot at its forward end for receiving an elevator guide rail, a laterally extending base having a slot vertically aligned with the slot of the box and supporting said box, a lid hinged on top of said box extending the major portion of the length of said box, means for fastening said lid on the box, an upright follower slidably in said box, and gravity means for impelling said follower forwardly in said box to feed a stick of grease to the slot in the forward end of said box.

70 6. A lubricator for elevator car guide rails comprising, an elongated box having an upright slot at its forward end for receiving an elevator guide rail, a laterally extending base having a slot vertically aligned with the slot of the box and supporting said box, a lid hinged on top of said box extending the major portion of the length of said box, means for fastening said lid on the box, an upright follower slidably in said box, and a pair of weights for impelling said follower forwardly in said box to feed a stick of grease to the slot in the forward end of the box under substantially uniform pressure during the length of travel of said follower.

75 HOWARD M. HUNTER.

80 7. A lubricator for elevator car guide rails comprising, an elongated box having an upright slot at its forward end for receiving an elevator guide rail, a laterally extending base having a slot vertically aligned with the slot of the box and supporting said box, a lid hinged on top of said box extending the major portion of the length of said box, means for fastening said lid on the box, an upright follower slidably in said box, and a pair of weights for impelling said follower forwardly in said box to feed a stick of grease to the slot in the forward end of the box under substantially uniform pressure during the length of travel of said follower.
